(57) **CLAIM**

The ornamental design for a switch, as shown and described.

DESCRIPTION

FIG. 1 is a front elevation view of our new design for a switch;
FIG. 2 is a rear elevation view thereof:

FIG. 3 is a top plan view thereof:

FIG. 4 is a bottom plan view thereof:

FIG. 5 is a right-side elevation view thereof:

FIG. 6 is a left-side elevation view thereof:

FIG. 7 is a perspective view thereof, as seen from the bottom,
front and right sides:

FIG. 8 is a perspective view thereof, as seen from the top, rear
and left sides; and,

FIG. 9 is a perspective drawing illustrating the switch in use,
as seen from the bottom, front and right sides.

The broken lines shown in the figure drawings are included
for the purpose of illustrating environmental detail as well as
unclaimed subject matter and form no part of the claimed
design.
